UNITED STATES PATENT OFFICE.

FREDERICK W. GORE, OF NEW YORK, N. Y.

AEROCRAFT.

1,123,729.

Specification of Letters Patent.

Patented Jan. 5, 1915.

Application filed September 23, 1909. Serial No. 519,195.

To all whom it may concern:

Be it known that I, FREDERICK W. GORE, a citizen of the United States, residing in the city of New York, borough of Brooklyn, county of Kings, and State of New York, have invented a certain new and useful Aerocraft, of which the following is a specification.

This invention is an aerocraft involving 10 in its construction elements which tend to establish forces that counteract or neutralize the air pressure and the wind pressure from any angle or direction while in flight, thus securing stability of the craft by overcom- 15 ing any tendency to capsize the craft or to deviate from a predetermined course by the prevalence of opposing air pressures or contrary winds.

The capacity for sustaining the weight 20 or load is secured by a novel construction of aeroplanes, one of which is a cross sectionally curved member extending in the direction of the length of the craft, whereas other of said aeroplanes are embodied in 25 the form of wing planes positioned at the respective sides of said curved member, said wing planes being preferably, although not essentially, curved or arched in order to increase the weight-carrying capacity of the 30 craft.

Stability of the craft is obtained, primarily, by the employment of the wing planes, and by the addition of certain resistance members or planes which cooperate 35 with the cross sectionally curved member and with the wing planes, respectively. Said resistance members or planes operate to secure the reactionary forces or effects which preclude deviation of the craft from its predetermined course by wind pressure 40 ahead, astern, or from either side, and which tend, also, to obviate capsizing of the craft by sudden gusts of wind from either side or at any angle relative to the craft or the 45 direction of its movement. One of the aforesaid resistance planes is positioned centrally with respect to the cross sectionally curved member, and in one embodiment of the invention, this particular plane is con- 50 structed to allow air to circulate therethrough in order to decrease the resistance. Said plane is, or may be, provided, also, with auxiliary planes adapted to be folded or unfolded relative to the plane, whereby 55 the effective area of the resistance plane may be increased or decreased. Other of said

resistance planes extend from the respective sides of the cross sectionally curved member, the axes of said resistance planes being at a right angle to the axis of the curved member, and each lateral resistance plane being positioned at an angle to the direction or line of flight. Still other resistance planes are employed in connection with the wing planes, and these resistance planes are so 60 positioned and proportioned that, in connection with the central longitudinal resistance plane, they offer such areas of surface to the air or wind pressure as will neutralize the effect of a sudden gust which 65 otherwise would capsize the craft or at least seriously impair its stability. 70

For steering the craft, provision is made for deflecting from normal positions the end portions of the wing planes whereby the 75 pressure against the deflected sections will turn the craft in the desired direction. Provision is made, also, for shielding the operator against the force of the air or wind in rapid flight through the air. Control of the 80 craft is obtained by devices placed within the convenient reach of the operator.

The accompanying drawings illustrate, without regard to details of construction, my new aerocraft in a preferred form of 85 construction, wherein—

Figure 1 is a view in side elevation of my new aerocraft. Fig. 2 is a front view thereof, that is to say, looking toward the left hand end of Fig. 1. Fig. 3 is a top plan view, and Fig. 4 is a bottom plan view. Fig. 5 is a vertical longitudinal section showing the shutter in position when the air ports are open, the feathering planes when in action, the motors, and the aviator's 90 station and seat. Fig. 6 is a view similar to Fig. 5, showing the shutter in position when the air ports are closed, the feathering planes housed, and the wheel base raised. Fig. 7 is a top plan view showing the central longitudinal resistance plane, the aviator's station and the lateral resistance planes, the cross sectionally curved plane and all other parts of the craft being omitted. Fig. 8 is a bottom plan view of the parts shown in Fig. 7, the middle part of the central longitudinal resistance plane being broken away. Fig. 9 is a cross section through the front part of the central longitudinal resistance plane showing the shutter housed 95 therein. Fig. 10 is a vertical cross section through the rear part of the central longi- 100 105 110

tudinal resistance plane illustrating the feathering vanes folded within said plane. Figs. 11 to 19 inclusive are diagrammatic views illustrating the main elements employed in the construction of the craft and the directions of action of the opposing forces whereby stability is secured. Fig. 20 is a table showing the acting and counter-acting forces.

In Figs. 7, 8, and 11 to 19 both inclusive there are shown diagrammatically the main elements employed in the construction of my aerocraft. These elements are a cross sectionally curved member, A, extending the full length of the craft, a resistance member, B, positioned within curved member, A, and also extending the full length of the craft, stability or resistance planes, C, C', the axes of which are at right angles to the axes of members, A, B, stabilizing or wing planes, D, D', at the respective sides of the craft, a propeller or propellers, E, E', E², and motive power for driving the propellers.

At the outset I desire to explain, as briefly as may be, the principles involved in my aerocraft whereby it is rendered capable of sustaining itself in the air during flight, and stability is secured. The elements just enumerated perform, mainly, the functions necessary to these ends, although their actions are supplemented by certain additional devices, to be hereinafter described.

To illustrate the forces acting on the air, we will assume that propeller, E, is rotating and that the craft is moving in the direction of length of members, A, B, and as indicated by the arrow, D, Figs. 11 and 13. The wind force, acting in the direction of arrow, F², Figs. 11 and 12, exerts pressure on the forward inclined stabilizing or resistance plane, C, and thus has a tendency to depress the forward part of members, A, B, on the center indicated at e (Figs. 11 to 16) as the axis of motion. The forward motion of the craft brings into action a counteracting force, indicated by the arrow, F', Figs. 13, 14 and 15, which force acts on the under surface or concave side of curved member, A (Figs. 13 and 14), said force, F', having a tendency to impart an upward inclination to member, A (Fig. 15). Thus we have the force, F², acting on stability or resistance plane, C, to exert a downward pressure (Figs. 11 and 12), and the force, F', acting on member, A, to exert an upward pressure (Figs. 13 and 14), such forces, F', F², opposing each other and producing what may be designated as a "couple." The forces are thus neutralized (Fig. 15) and stability is secured when the craft moves in the direction of arrow, D, Figs. 11 to 15, inclusive.

When the aerocraft is in flight, its motion may be said to "cut out" a column of air, or in other words, the air immediately surrounding the craft may be said to be denser

than the remaining air, the denser air enveloping the craft serving as a supporting medium for said craft. In its flight, the denser air is forced in at the forward part of curved member, A, mainly by the action of propeller, E, and this current of air, coming into contact with the forward resistance plane, C, is deflected upward, see the arrows in Fig. 16, causing a compression at the apex of the lateral resistance planes, C, C', after passing which apex the air expands, in a measure, and makes its exit at the rear of curved member, A. This current of air passing through curved member, A, is an ever present force which tends to exert lifting and stabilizing forces on the craft.

In Figs. 17 and 18, members, A, B, are shown as having braces, 1^a, 2^a, stabilizing or resistance planes, C, C', being omitted. The forces acting on the exposed side or convex surface of member, A, are shown diagrammatically in Fig. 17 when the chord of said member, A, is horizontal; but should members, A, B, be tilted sidewise so as to assume the angle shown in Fig. 18, and fixed in that position, then the forces acting on the members, A, B, as shown in Fig. 18, would be similar to the forces acting, in part, to force the members, A, B, in the aerocraft to their normal position.

To illustrate the acting and counteracting forces exerted upon the craft under a side pressure from the right, Fig. 19 is added to the drawings. Said figure illustrates members, A, B, wing planes, D, D', and resistance planes, F, F', G, G', coöperating with the stabilizing wing planes, stabilizing resistance planes, C, C', being omitted. It is assumed that the craft is traveling head on toward the observer, and that a heavy wind force is acting in the direction of arrow, F². This extreme angle is chosen to bring into operation the perpendicular resistance plane F' and the wing plane D'. The perpendicular resistance planes F, F', G, G' are secured to the wing planes D and D' and are parallel with the curved member A. The under surface of the wing planes D, D' will be considered in this instance. The total wing plane area of each wing plane is divided into two parts, respectively, by the perpendicular resistance planes F, F'. The force of the wind acting on the surface of the wing plane at the right of the perpendicular resistance plane F exerts a pressure equal to 3.33 lbs. per square foot of surface. This pressure is what may be termed the acting force F₄. By introducing the perpendicular resistance plane F a different angle of inclination is presented to the wind force, therefore, the pressure acting on the perpendicular resistance plane F is greater than the pressure acting on the surface of the wing plane D at the right of the perpen- 130

icular resistance plane F. This force is represented by the force $F.5=5$ lbs. per square foot. This may be termed the counteracting force F.5. The area of the wing 5 plane D, to the leeward of the perpendicular resistance plane F, is protected from the direct force of the wind. The dotted line extending from the lower extremity of the perpendicular resistance plane F, to the surface 10 of the wing plane D, shows the extent of the protected area of the wing plane D. The exposed or effective area is acted upon by the force $F.6=4.50$ lbs. per square foot. The curved member A, from where the wing 15 plane D is joined thereto presents various angles of inclinations, therefore, the pressure varies. The forces acting on the curved member A, and the effective area of member B are shown in the table marked F.A. 20 These may be termed counteracting forces F.A. which aggregate a pressure of 4.1 lbs. per square foot. The extent of the protected area of the wing plane D is shown by the dotted line extending from the left side of 25 the curved member A, to the under surface of the wing plane D'. This area being to the leeward of the curved member A is not exposed to the direct force of the wind. The perpendicular resistance plane F', however, receives the full force of the wind, 30 and the force is represented by $F.8'$ equals 5 lbs. per square foot of surface. This force may be termed a counteracting force, $F.8'$. The extent of the protected area of the 35 wing plane D' at the left of the perpendicular resistance plane F' is shown by the dotted line extending from the lower extremity of the perpendicular resistance plane F' to the under surface of the wing 40 plane D'. The exposed or effective area of the wing plane D' is acted upon by the force, $F.9=3.33$ lbs. per square foot of surface. This may be termed the counteracting force F.9. Aggregating all the forces acting on 45 the aerocraft at the specified angle, it is found that the average lifting or acting force of 3.91 lbs. per square foot (see table Fig. 20) meets with an average counteracting force of 4.21 lbs. per square foot, and, 50 hence, the area presented to the wind pressure, exerting a force of 3.91 lbs. per square foot, which tends to capsize the craft, would be opposed or counteracted by an area against which the wind exerts a pressure 55 of 4.21 lbs. per square foot. Therefore the factor of safety is more than sufficient to take care of very sudden and strong gusts of wind which, perchance, might strike aerocraft without a moment's warning. 60 The respective areas can therefore be proportioned accordingly. To illustrate, if the under surface of the wing plane D at the right of the perpendicular resistance plane F, contains an area, say of 10 square 65 feet, the pressure would amount to 33.3 lbs.

Now since the perpendicular resistance plane F offers a resistance of 5 lbs. per square foot, the area of said plane is so proportioned that the area in square feet multiplied by the lbs. per square foot would produce a pressure slightly in excess of the acting force F.4. for example, say, 6.7 square feet equals the area of the perpendicular resistance plane F. The area 6.7 square feet times the pressure, 5 lbs. per square foot equals 33.5 lbs. equals the counteracting force F.5. thereby neutralizing the effect of a sudden gust of wind on the side of the craft. 70

The calculations are based on the formula 80

$$P^a = P \sin. i^{1.84} \cos. 1-1.$$

One tenth of the full value is used for illustrative purposes.

Proceeding now to a detail description of 85 the craft constructed as shown in Figs. 1 to 10 inclusive, the cross sectionally curved plane, A, may be composed of fabric, such as balloon silk stretched around a suitable frame work in the ordinary manner of constructing planes for aerial machines, but it is evident that thin sheet metal of light weight may be employed in the construction of said cross sectionally curved plane. I 90 may employ aluminum in the manufacture of the plane, A, and in this event the aluminum shell forming the plane should be reinforced by bands indicated at a in Figs. 1 and 3. The end portions of the cross sectionally curved plane are cut inclined or 95 beveled at a' , a^2 , respectively, forming an angle of inclination of said end portions, a' , a^2 , to the longitudinal axis of the plane, A, being about 20 or 30 degrees according as the craft is to be built for speed purposes or for ordinary commercial purposes. 100

The resistance plane, B, is positioned centrally with respect to curved plane, A. Said resistance plane, B, is partly within 110 the curved plane, the upper edge of said resistance plane being joined to the middle portion of the curved plane in any suitable rigid way. The resistance plane extends the full length of the curved plane and of 115 the craft, and this resistance plane is substantially rectangular in form so that the end portions of said resistance plane are exposed beyond the beveled end portions, a' , a^2 , of said curved plane. The resistance 120 plane, B, is of greater width than the radius of the semi-circular plane, and thus the lower edge of plane, B, is exposed below the corresponding lower edge of the curved shell constituting plane, A, all as clearly 125 shown in Figs. 1 and 2 of the drawings, and indicated in the diagrammatic Figs. 15, 16, 17, 18 and 19 of said drawings.

The aviator's station, G, is shown as a 130 box-like inclosure intersecting with the lon-

itudinal resistance plane, B, the side walls, g, of said station being curved toward each other and meeting said resistance plane, as shown in Fig. 7. The aviator's station is 5 equipped with a suitable seat, G', for the accommodation of the aviator, but the upper and lower parts of this station are open in order that the aviator may easily gain access to or leave said station.

10 The stability or resistance planes, C, C', extend from the respective sides of the central longitudinal plane, B, said stability planes, C, C', being at a right angle to plane, B, and one or both of said resistance planes crossing the aviator's station, G. These lateral planes, C, C', are at an angle to each other and they are inclined to the longitudinal axis of the craft, see Figs. 1, 5, 6, 7 and 8, and diagrammatic views 11, 15 20 12, 15 and 16. The forward resistance plane, C, is inclined downwardly and forwardly, whereas the rear resistance plane, C', is inclined downwardly and rearwardly, said rear resistance plane, C', partly closing 25 the lower side of station, G.

Stabilizing wing planes, D, D', are positioned at the respective sides of the craft, each wing plane having a straight inner edge which is attached in a suitable way to the 30 shell composing the cross sectionally curved plane, A. Each wing plane is of the shape shown more particularly in Figs. 3 and 4 of the drawings, by reference to which it will be seen that said wing plane is approximately triangular in form, with the apex of the triangle at the rear. The wide forward portion of each stabilizing wing plane, D, D', is bounded by curved edges d, and an inclined edge, d', thus producing 35 40 45 an approximately pointed flexible member, D², the pointed extremity d³ of which is adapted to cleave through the air. The inclined or curved outer edge, d', of each wing converges with respect to the straight inner edge, d³, of said wing so as to form a tapering rear portion, D³. Each stabilizing wing may be rigidly fastened at its straight inner edge, d³, to the craft, or said wing may be pivotally connected to the 50 craft, or said wing may be detachably fastened to the craft, as may be found most desirable. In Figs. 1, 2, 3 and 4 I have shown each stabilizing wing plane as being attached rigidly to the craft, and said wing 55 plane is braced or stayed by suitable truss work indicated generally by the reference character, h, said truss work being shown more clearly in Fig. 2 of the drawings. Each wing plane consists of a suitable skeleton frame over which the fabric is stretched so as to be kept in a taut condition. The end portions, D², D³, of each wing plane are flexible or pliable so that they may be deflected upwardly or downwardly with re-

spect to the intermediate portions of said 65 wing plane, said portions of the wing plane intermediate the pliable or flexible members, D², D³, being substantially rigid. As shown, the stabilizing wing planes extend outwardly from the curved plane, A, and 70 each wing plane is preferably arched or curved in cross sectional contour, see Fig. 2, whereby wing planes, D, D', and curved plane, A, afford the desired weight carrying capacity to the craft. 75

For the purpose of steering the craft, I provide means for adjusting the flexible members, D², D³, of the wing planes, D, D', a separate rudder being omitted. From the upper side of flexible member, D², of each 80 wing plane extends an operating wire or cable 1, the same being securely fastened at 2 to said member, D², and running over a guide member 3, said wire 1 leading to aviator's station, G, and providing means 85 whereby the member, D², may be drawn upwardly. From the upper side of flexible member, D³, at the rear of each wing plane, extends an operating cable or wire 4, the same being fastened rigidly to the tail point 90 at 5 and leading from a guide member 6 so as to extend to operator's station, G, said wire 4 affording means for raising the flexible member, D³, at the rear edge of 95 the wing plane, all as clearly shown in Fig. 3.

Wires 1 and 4 enable members, D², D³, of each wing plane to be raised, and similar wires 7 and 8 are provided on the under side of each wing plane for the purpose of 100 depressing said flexible members, D², D³, in order that they may be drawn downwardly. As shown in Fig. 4, wire 7 is fixed at the point 7^a to the under side of flexible member, D², of each wing plane, said wire 105 7 running over a suitable guide 9 and extending to operator's station, G, so that said member, D², may be drawn downwardly. The other operating wire 8 is fastened at the point 10 to the under side of flexible wing member, D³, of each wing plane, said wire 110 8 extending forwardly to operator's station, G, for the purpose of enabling the operator to pull downwardly on the wing member, D³. 115

From the foregoing description it will be understood that flexible members, D², of the wing planes, D, D', may be separately drawn downward by pulling on operating wires 7-7, but should it be desired 120 to raise the forward members, D², of said wing planes, D, D', or either of said members, D², wires 1-1 may be separately operated. In a similar manner the wing members, D³, of wing planes, D, D', may be drawn downwardly by operating the 125 wires 8-8, but should it be desired to raise the wing members, D³, or either of them, the proper wires 4 are pulled by the oper-

ator occupying the station G. It will be understood that the forward members D² of the wing planes may be operated separately or collectively. Also the rear members D³ may be operated separately or collectively. To steer to the right, the rear member D³ on the right side of the craft is drawn into position by means of the wire 4, on the right side. To steer to the left, the rear member D³ on the right side of the craft is drawn into position by means of the wire 4, on the left side. To ascend, the rear members D³ on both sides of the craft are drawn simultaneously into position by means of the wires 4—4. If it is desired to ascend at a greater angle, the forward members D² of the wing planes D, D' are drawn simultaneously into position by means of the wires 1—1. To descend the rear members are drawn simultaneously into position by means of the wires 8—8. If a quicker descent is desired the forward members D² are drawn simultaneously into position by means of the wires 7—7. By making the forward and rearward members of the wing planes flexible or pliable and providing means such as described for operating said members of the respective planes, the operator is able to send the craft in an upward direction or in a downward direction, and to steer the craft right or left as may be desired, said craft having a tendency, when the parts are in normal position, to pursue a horizontal course when the propeller, E, is rotated at the required speed.

The propeller, E, is positioned, preferably, at the extreme forward end of the craft. The shaft, e, of said propeller ranges lengthwise of the craft for a suitable distance, and it is supported at the upper central part of curved plane, A, see Figs. 1, 2, 5 and 6 of the drawings. The propeller is exterior to the planes, A, B, at the extreme forward end thereof, and it operates to send a current of air under curved plane, A, for the purpose hereinbefore explained. Said propeller is driven from a suitable motor or engine, H, the position of which is indicated in Fig. 5 and 6. Said motor or engine is within curved plane, A, forward of aviator's station, G, and above resistance plane, C, and the shaft of said motor is connected by suitable belting or gearing to propeller shaft, e.

For the purpose of increasing the lifting capacity of the craft so that the operator is enabled to ascend to higher altitudes, I employ auxiliary propellers, E', E², shown in Figs. 1, 2, 5 and 6. Said auxiliary propellers are shown as consisting of a hub and tangential arms having curved blades, but the particular form of the propeller is not material. Said propellers are positioned at the respective sides of the craft

exteriorly to curved plane, A, and resistance planes, C, C'. The propellers are just forward of aviator's station, G, and they are adapted to be driven by an auxiliary engine or motor, H', see Fig. 5 and 6, said motor being below the apex of lateral resistance planes, C, C'. Of course, suitable provision is made for throwing the auxiliary motor into action, but normally the motor, H, for propeller, E, is in operation.

Provision is made for varying the effective area of longitudinal resistance plane, B, and in Figs. 5, 6, 9, and 10 of the drawings I have shown different embodiments of devices for accomplishing this purpose. At 80 the forward part of said resistance plane, B, is a slideable shutter, I, the same being housed or contained within a pocket, i, which is formed in said forward part of plane, B. Said pocketed part, i, of plane, B, is provided with a series of slots, i', see Fig. 9, and within the pocket is positioned the shutter, I, said shutter having slots, i², which are adapted to be shifted into and out of register with the slot, i', of plane, B. 90 When the shutter is moved in a forward direction so as to occupy the position of Fig. 6, the slots, i², of said shutter are cut of register with the slot, i', of the plane, and thus the solid part of said shutter closes the 95 slots, i', for the purpose of precluding the circulation of air through the slotted part of the plane. The shutter is supported at its edges by suitable rollers, i³, see Figs. 5 and 6, to insure easy sliding movement thereto, and with the shutter is associated suitable operating means for imparting said sliding movement thereto. The operating means in one embodiment of the invention consists of a sliding rod, I', extending 105 into the aviator's station, G, so as to be reached conveniently by the operator occupying seat, G', the forward end portion of said rod, I', being connected by a link, I², to the rear part of the shutter. It is evident 110 that the operator may draw the rod rearwardly for the purpose of moving shutter, I, to the position of Fig. 5, whereby the slots, i², of said shutter are in register with the slots, i', of plane, B, thus allowing air 115 to circulate through the slotted part of the plane and decreasing the resistance offered by said plane to the wind pressure. Means are provided, also, for varying the effective area of the resistance plane at the rear part thereof, and in Figs. 6 and 7 of the drawings I have shown said means in the form of feathering planes or vanes, J, J'. Said rear part of longitudinal resistance plane, B, is constructed to form a pocket j, said pocket 125 extending lengthwise of plane B, from a point immediately in rear of aviator's station, G, toward the extreme rear end of said plane, B, as shown more clearly in Figs. 5, 6 and 10. The feathering planes 130

are of the tapering form represented in Figs. 5 and 6, and they are positioned so as to be inclosed or housed within said pocket, j , respectively. Said planes, J, J' , 5 are mounted at their forward ends on short axles or pivots, k , and from these axles extend crank arms, k' , which are connected by pivoted links to arms, k^2 , on a cross head, K . This cross head is attached to a sliding 10 rod, K' , which is held normally in one position by a coiled spring, K^2 , said spring acting to impel the rod, K' , and cross head, K , in a forward direction for the purpose of moving the arms, k', k^2 , to the position of 15 Fig. 5, whereby the vanes, J, J' , are moved on their pivots, k , to the open positions shown in Fig. 5. The vanes are thus adapted to be exposed above and below the pocketed portion j of the resistance plane, B , at 20 the rear part thereof, and said vanes, J, J' , substantially increase the effective area of the resistance plane exposed to wind or air pressure. The operating rod, K' , is under the control of the aviator occupying seat, 25 G' , through the instrumentality of a treadle, J^2 , said treadle being connected by a rod, j^3 , to the crank arm, j^4 , which connects with the forward part of sliding rod, K' . It is evident that suitable means may 30 be provided for locking the rod, K' , against the tension of spring, K^2 , but when the locking device is released, then the spring, K^2 , operates to quickly throw the feathering planes, J, J' , to their open or exposed positions. Normally, however, the parts are 35 adjusted for the feathering planes to be folded and retained within the pocket j of the longitudinal resistance plane, B .

It will be understood that the shutter, I , 40 and the feathering planes are operated separately or independently by devices within convenient reach of the aviator, and, furthermore, that the shutter may be adjusted to its open position at the same time 45 that the feathering planes are opened or spread, substantially as shown in Fig. 5.

Previous to flight, the craft is supported on the ground or other surface in the inclined position, substantially as shown in Fig. 1, through the instrumentality of a wheeled base. One part of this base is a wheeled axle, L , secured fixedly to the frame of the aerocraft well toward the rear part thereof, as shown in Figs. 1, 5 and 6. The 50 other and forward part of the wheel base is movable, and as shown in Figs. 1, 5 and 6, the front wheeled axle, L' , is carried by a movable support, L^2 , the latter being pivoted on a cross shaft, l , attached to the 55 frame work. This cross shaft is provided with an arm, l^2 , to which is attached an operating cable, l^2 , the rear part of which cable is fastened to a manually operated lever, L^3 , said lever being within convenient 60 reach of the operator. When the craft is at 65

rest, the front part of the wheel base is lowered so that the axles, L, L' , will support the craft on the ground for the weight-carrying planes to occupy the inclined position shown in Fig. 1, but after the craft is started, the operator should manipulate lever, L^3 , for the purpose of raising the wheeled axle, L' , to the raised position shown in Fig. 6.

Depending from wing planes, D, D' , are 70 resistance planes, F, F' , two or more of said depending resistance planes being provided on each wing plane, as shown in Figs. 1, 2 and 4 of the drawings. Each wing plane is provided, furthermore, with upwardly extending resistance planes, G^2, G^3 , as shown in Fig. 2. Said resistance planes are parallel to the longitudinal axis of planes, A, B , and the resistance planes offer surfaces above and below the wing planes for the 80 pressure of wind or air, whereby the resistance planes, F, F', G^2, G^3 , operate to counteract the force of a side wind pressure in either direction which would tend to so act on the wing planes as to invert or capsize the craft. In addition to the longitudinal resistance planes which extend upwardly from and depend below the wing planes, D, D' , said wing planes are provided with inclined depending resistance 90 planes, M , as shown in Figs. 3 and 4. These depending planes are just forward of the flexible tail portions, D^2 , of said wing planes and they afford yielding surfaces for wind pressure near the tail end of the craft. 100

The operation is as follows: With the machine in the position shown in Fig. 1, the aviator takes his seat and operates the wires 1-1 for the purpose of raising the forward part or members, D^2 , of wing planes, D, D' . Motor, H , is now started into operation for the purpose of rotating propeller, E , at the required speed, and said propeller generates a current of air which is directed rearwardly and below the machine, particularly against 110 the under side of the cross sectionally curved plane, A , whereby the machine is caused to ascend. When the machine is clear of the ground the operator lifts the forward part, L' , of the wheel base. As 115 headway is gained and the aviator wishes to climb at a greater angle, the wires 4-4 are operated for the purpose of raising the tail portions, D^2 , of the wing planes so as to cause the machine to ascend at a sharp angle. When the desired height is attained the rear portions, D^2 , of the wing planes are 120 allowed to assume their normal positions so as to occupy substantially the same plane as the intermediate portions of the wing planes, 125 and if desired, the forward members, D^2 , of said wing planes are lowered at a slight angle in order to keep the craft in the desired position. Under ordinary conditions of navigation, the different parts of the 130

craft are in the position shown in Fig. 6, wherein the wheel base is raised, the shutter, I, is moved forwardly to the closed position, and the feathering vanes, J, J', are 5 housed within the rear part of the resistance plane, B, motor, H, operating to drive the propeller, E, at the required speed. Should the machine be caught in a heavy wind and be required to stay up in the air for the reason that a landing would not be desirable, the operator manipulates rod, I', to open the shutter, I, and manipulates treadle, J², for the purpose of releasing spring, K², so as to move the feathering vanes, J, J', to their 10 open or spread positions as shown in Fig. 5. With the slots, i', in the forward part of the resistance plane, B, opened by the adjustment of the shutter, the wind pressure at the forward part of the craft is reduced, and at 15 the same time, the vanes, J, J', when spread to their open positions, increase the effective area of resistance plane, B, at the rear part thereof so that the wind pressure on the rear part of plane, B, will exceed the wind pressure 20 on the front part of said plane. With the shutter, I, opened and the feathering planes exposed, as shown in Fig. 5, the machine will swing around so as to come head-on into the wind. The machine is now in a 25 position where it may readily climb to a higher altitude in order to escape the force of contrary winds, and to accomplish this end the operator should start auxiliary motor, H', into action, thereby operating the 30 auxiliary propellers, E', E². Should the operator find that he is too close to the wind, the wires 1, 4, 7 and 8 may be manipulated so as to steer the craft in the desired direction, and enable said craft to swing off with 35 respect to the wind in the desired manner. For the purpose of descending and alighting, the operator temporarily cuts motors, H, H', out of action, and thus permits the 40 machine to glide earthward, the power being thrown on at intervals so that the machine will descend and strike the earth with slight force. Should the power fail entirely, the operator can alight easily by manipulating the wires which control flexible 45 members, D², D³, of the wing planes, and just before alighting, the wheel base, L' is lowered so that the machine will be supported on its carrying wheels.

Having thus fully described the invention, what I claim as new, and desire to secure by Letters Patent is:

1. In an aerocraft, the combination of a weight-carrying plane extending lengthwise of the craft, said plane being curved 50 in cross section and the under concave surface thereof being imperforate, a stabilizing plane angular in cross section, said stabilizing plane being positioned for the central line thereof to lie substantially at a right 55 angle to the longitudinal axial line of the

weight-carrying plane, and propelling mechanism for driving the craft in the direction of the length of the weight-carrying plane.

2. In an aerocraft, the combination of a longitudinal weight-carrying plane, said plane being curved in cross section, and stabilizing planes positioned at the respective sides of said longitudinal plane, said stabilizing planes being substantially of inverted V-shape in cross section.

3. In an aerocraft, the combination of a weight-carrying plane extending longitudinally of the craft, said plane being arc-shaped in cross section and closed at the top 80 and sides and open at the bottom, and a resistance plane extending lengthwise of said arc-shaped longitudinal plane, and positioned within the closed top and side portions thereof, said resistance plane depending below the respective sides of the arc-shaped plane so that the side surfaces of said resistance plane are exposed to wind and air pressure.

4. In an aerocraft, the combination of a cross sectionally curved weight-carrying plane extending in the direction of the length of the craft, wing-planes positioned exteriorly to said weight-carrying plane, and a stabilizing plane angular in cross section, said stabilizing plane being positioned transversely with respect to the weight-carrying plane and below the wing-planes.

5. In an aerocraft, the combination of a cross sectionally curved weight-carrying 100 plane extending in the direction of the length of the craft, a stabilizing plane positioned transversely with respect to the weight-carrying plane, said stabilizing plane being composed of members inclined 105 reversely with respect to each other, and mechanism for propelling the craft in the direction of the length of said weight-carrying plane.

6. In an aerocraft, a cross sectionally 110 curved plane extending in the direction of the length of the craft, a plurality of resistance planes inclined oppositely to each other and extending transversely with respect to the length of said curved plane, 115 and propelling mechanism.

7. In an aerocraft, a cross sectionally curved plane extending in the direction of the length of the craft, a resistance plane positioned centrally with respect to the 120 curved plane and extending lengthwise thereof, transverse resistance planes inclined with respect to the curved plane, and propelling mechanism.

8. In an aerocraft, a cross sectionally 125 curved plane extending in the direction of the length of the craft, a resistance plane positioned centrally with respect to the curved plane and extending lengthwise thereof, resistance planes positioned trans- 130

versely to, and inclined with respect to, the curved plane, wing planes at the respective sides of the curved plane, and propelling mechanism.

5. In an aerocraft, a cross sectionally curved plane extending in the direction of the length of the craft, a resistance plane positioned centrally with respect to the curved plane and extending lengthwise thereof, the end portions of said curved

10 planes being cut away, thereby exposing the corresponding end portions of said central resistance plane, inclined resistance planes positioned exteriorly to the curved plane, and propelling mechanism.

15 9. In an aerocraft, a cross sectionally curved plane extending in the direction of the length of the craft, the concave under side of said plane being open for the free

20 ingress of air, stabilizing planes positioned transversely to said curved plane, said stabilizing planes being of angular form in cross section, and propelling mechanism operating to establish below said curved plane

25 a zone of air which is of greater density than the surrounding atmosphere.

10. In an aerocraft, a cross sectionally curved plane extending in the direction of the length of the craft, the concave under side of said plane being open for the free

20 ingress of air, stabilizing planes positioned transversely to said curved plane, said stabilizing planes being of angular form in cross section, and propelling mechanism operating to establish below said curved plane

25 a zone of air which is of greater density than the surrounding atmosphere.

11. In an aerocraft, a cross sectionally curved plane extending in the direction of the length of the craft, the concave under side of said plane being open for the free

30 ingress of air, propelling mechanism adapted to establish below the curved plane a zone of air which is of greater density than the surrounding atmosphere, a resistance

35 plane positioned within, and extending lengthwise of, the curved plane, the lower portion of said resistance plane being exposed to side wind or air pressure, and stabilizing planes coöperating with said curved

40 plane.

12. In an aerocraft, the combination of a longitudinal plane curved in cross section, a resistance plane extending lengthwise of said longitudinal plane and arranged for

45 the lower part thereof to be exposed to side wind and air pressure, stabilizing planes positioned exteriorly to the longitudinal plane and at the respective sides thereof, and wing planes extending outwardly from

50 and lengthwise with respect to said longitudinal plane.

13. In an aerocraft, a cross sectionally curved plane extending in the direction of the length of the craft, the concave under

55 side of said plane being open for the free ingress of air, propelling mechanism adapted to establish below the curved plane a zone of air which is of greater density than the surrounding atmosphere, a resistance plane

60 extending lengthwise of the curved plane and exposed to side wind or air pressure, wing planes at the respective sides of the curved plane and the central resistance plane, and a stabilizing plane positioned

65 transversely to the curved plane and the

central longitudinal plane, said stabilizing plane being angular in cross section.

14. In an aerocraft, a cross sectionally curved plane extending in the direction of the length of the craft, the concave under

70

side of said plane being open for the free ingress of air, propelling mechanism adapted to establish below the curved plane a zone of air which is of greater density than the surrounding atmosphere, a resistance plane

75

extending lengthwise of the curved plane and occupying a predetermined fixed relation thereto, said resistance plane extending below the lower edges of the curved plane, whereby the lower part of said resistance

80

plane is exposed to side wind or air pressure, and means for varying the effective area of the central longitudinal plane.

15. An aerocraft provided with a cross sectionally curved plane, open on its lower side, a longitudinal resistance plane exposed to wind pressure below and at the ends of

85

said curved plane, stability planes laterally of said curved plane, the lower part of said resistance plane extending below the bottom

88

edges of said curved plane, and propelling mechanism adapted to establish below the craft a zone of air which is of greater density than the surrounding atmosphere.

16. In an aerocraft, the combination of a longitudinal plane curved in cross section, wing planes positioned at the respective sides of said longitudinal planes and extending lengthwise thereof, stabilizing planes positioned below the wing planes and trans-

90

versely with respect to the longitudinal plane, and propelling mechanism operating to establish below said curved longitudinal plane a zone of air which is of greater density than the surrounding atmosphere.

95

17. An aerocraft provided with a plu-

100

rality of weight-carrying planes extending in the direction of the length of the craft, one of said weight-carrying planes being curved in cross section, a central resistance

105

plane extending lengthwise of the craft, said resistance plane being increased partially by the cross sectionally curved weight-

110

carrying plane and the lower part of said resistance plane depending from said curved weight-carrying plane, means for varying the effective area of said central plane,

115

propelling mechanism, and stabilizing planes coöperating with the weight-carrying

120

planes.

125

18. In an aerocraft, the combination of a weight-carrying plane extending in the direction of the length of the craft, said plane being curved in cross section and having the under side thereof open to the free ingress

130

of air, a stabilizing plane positioned transversely to said weight-carrying plane, said stabilizing plane being composed of mem-

135

bers inclined with reference to each other, wing planes positioned at the respective

- sides of the weight-carrying plane, and means for propelling the craft in the direction of the length of the weight-carrying plane.
- 5 19. In an aerocraft, the combination of a weight-carrying plane extending lengthwise of the craft, said plane being semi-circular in cross section and the under concave side thereof being open for the free ingress of 10 air, propelling means operating to establish below said weight-carrying plane a zone of air greater in density than the surrounding air, a resistance plane extending lengthwise of and depending below said semi-circular 15 plane, and a stabilizing plane positioned transversely to the semi-circular plane and the resistance plane. 70
20. In an aerocraft, the combination of a weight-carrying plane extending lengthwise of the craft, said plane being semi-circular in cross section and the under concave side thereof being open for the free ingress of air, propelling means operating to establish below said weight-carrying plane a zone of 25 air greater in density than the surrounding air, a resistance plane extending lengthwise of and depending below said semi-circular plane, and a stabilizing plane positioned transversely to the semi-circular plane and 30 intermediate the ends thereof, said stabilizing plane being composed of members inclined oppositely to each other. 80
21. An aerocraft provided with a longitudinal cross sectionally curved plane, means for moving said plane in the direction of its length, a resistance plane lengthwise of said curved plane, and a shutter for varying the effective area of said resistance plane. 85
- 40 22. An aerocraft provided with a longitudinal cross sectionally curved plane, means for moving said plane in the direction of its length, a resistance plane lengthwise of said curved plane, said resistance 45 plane having openings for the passage of air, and a shutter movable to close or open said openings in the plane. 90
- 50 23. An aerocraft provided with a longitudinal cross sectionally curved plane, means for moving said plane in the direction of its length, a resistance plane lengthwise of said curved plane, said resistance 55 plane having openings for the passage of air, a slideable shutter adapted to close or expose said openings, and means for operating the shutter. 95
- 60 24. An aerocraft provided with a longitudinal cross sectionally curved plane, means for moving said plane in the direction of its length, a resistance plane lengthwise of said curved plane, and feathering planes co-operating with the resistance plane for varying the effective area thereof. 100
- 65 25. An aerocraft provided with a longitudinal cross sectionally curved plane, means for moving said plane in the direction of its length, a resistance plane lengthwise of said curved plane, and a stabilizing plane positioned transversely to the two named longitudinal planes, said stabilizing plane being angular in cross section, an aviator's station within the semi-circular plane and substantially at the rear of the stabilizing plane, propelling mechanism, and steering mechanism. 105
- 70 26. An aerocraft provided with a longitudinal cross sectionally curved plane, means for moving said plane in the direction of its length, a resistance plane lengthwise of said curved plane, feathering vanes, at the rear part of said resistance plane, and means operated at will for adjusting said feathering vanes. 110
- 75 27. An aerocraft provided with a longitudinal cross sectionally curved plane, means for moving said plane in the direction of its length, a resistance plane lengthwise of said curved plane, feathering vanes foldable within said resistance plane, and means operated at will to adjust said vanes to positions exposed beyond the resistance plane, whereby the area of said plane may be substantially increased. 115
- 80 28. In an aerocraft, weight-carrying planes, a longitudinal resistance plane, means for decreasing the effective area of said resistance plane at the forward part thereof, and means for increasing the effective area at the rear part of said plane. 120
- 85 29. In an aerocraft, weight-carrying planes, a longitudinal resistance plane, pivoted planes foldable within the resistance plane, a movable rod connected operatively with said pivoted planes, means for normally impelling the rod in one direction, and means for operating said rod. 125
- 90 30. In an aerocraft, the combination of a substantially imperforate weight-carrying plane curved in cross section, said plane being open at its under side and respective ends, a stabilizing plane positioned transversely with respect to, and intermediate the ends of, said weight-carrying plane, propelling mechanism, and wing planes positioned exteriorly to the weight-carrying plane and at the respective sides thereof, said wing planes extending lengthwise of the weight-carrying plane and co-operating therewith in sustaining the weight of the load. 130
- 95 31. In an aerocraft, the combination of a longitudinal plane substantially semi-circular in cross section, a second longitudinal plane positioned partly within said semi-circular plane and depending therefrom, a stabilizing plane positioned transversely to the two named longitudinal planes, said stabilizing plane being angular in cross section, an aviator's station within the semi-circular plane and substantially at the rear of the stabilizing plane, propelling mechanism, and steering mechanism. 135
- 100 32. In an aerocraft, a cross sectionally curved plane, a longitudinal plane positioned partly within said cross sectionally curved plane, a stabilizing plane positioned transversely to the two named planes, said stabilizing plane being angular in cross section, an aviator's station within the semi-circular plane and substantially at the rear of the stabilizing plane, propelling mechanism, and steering mechanism. 140

- curved plane extending in the direction of the length of the craft, a central resistance plane lengthwise of said curved plane, a stabilizing plane positioned transversely with respect to said curved plane and intermediate the ends thereof, a propeller adapted to generate a current of air which acts upon the concave surface of said curved plane, and auxiliary propellers positioned below, and intermediate the ends of, said curved plane.
38. In an aerocraft, a cross sectionally curved plane extending in the direction of the length of the craft, a central resistance plane lengthwise of said curved plane, a stabilizing plane positioned transversely to the curved plane and intermediate the ends thereof, a propeller adapted to generate a current of air which acts upon the concave surface of said curved plane, auxiliary propellers below said stabilizing plane, and separate motors for operating the propeller and the auxiliary propellers independently of each other.
39. In an aerocraft, the combination of a cross sectionally curved plane extending in the direction of the length of the craft, wing planes at the respective sides of said curved plane, a stabilizing plane angular in cross section and rigid with said curved plane, said stabilizing plane being positioned transversely with respect to said curved plane, and separate stabilizing planes positioned below and coöperating with said wing planes.
40. In an aerocraft, the combination of a cross sectionally curved plane extending in the direction of the length of the craft, a stabilizing plane positioned transversely with respect to the curved plane, means for propelling the craft in the direction of the length of said curved plane, wing planes positioned at the respective sides of said curved plane, and separate stability planes depending from said wing planes, said depending stability planes being approximately parallel to the longitudinal axis of the curved plane.
41. In an aerocraft, the combination of a cross sectionally curved plane extending in the direction of the length of the craft, a stabilizing plane positioned transversely to the curved plane, and intermediate the ends thereof, means for propelling the craft in the direction of the length of said curved plane, wing planes at the respective sides of said curved plane, and other stabilizing planes carried by, and depending from, said wing planes, said stabilizing planes being approximately parallel to the longitudinal axis of said curved plane.
42. An aerocraft having a cross sectionally curved plane extending lengthwise of the craft, arched wing planes extending outwardly from said curved plane, a stability plane angular in cross section and positioned transversely to the curved plane, other stability planes depending from the wing planes, and propelling mechanism.
43. An aerocraft having a cross sectionally curved plane extending lengthwise of the craft, a stability plane angular in cross section and positioned transversely to said curved plane, propelling means, wing planes at the respective sides of the craft, each wing plane being provided at the forward end with a flexible tip, and means operable at will for changing the position of said flexible tip with reference to the surface of the wing plane.
38. In an aerocraft, the combination of a cross sectionally curved plane extending lengthwise of the craft, a stability plane positioned transversely with respect to said curved plane, propelling means, wing planes extending outwardly from said curved plane at the respective sides thereof, each wing plane being provided at the front part thereof with a flexible tip, and separate means operable at will for changing the position of said flexible tips relative to the surfaces of the wing planes.
39. In an aerocraft, the combination of a cross sectionally curved plane extending lengthwise of the craft, a stability plane positioned transversely to said curved plane, propelling means, wing planes curved in cross section and extending outwardly from the respective sides of the curved plane, each wing plane being provided at its rear part with a flexible tip, and separate means for independently adjusting the flexible tips of the respective wing planes.
40. In an aerocraft, the combination of a cross sectionally curved plane extending lengthwise of the craft, a stability plane positioned transversely with respect to said curved plane, propelling means, wing planes extending outwardly from the respective sides of the curved plane, each wing plane being provided at the front part and at the rear part thereof with flexible tips, and a plurality of separate adjusting devices for individually changing the positions of said flexible tips with reference to the surfaces of the wing planes.
41. In an aerocraft, a cross sectionally curved plane extending lengthwise of the craft, a stability plane positioned transversely to the curved plane, propelling means, wing planes extending outwardly from the respective sides of the curved plane, stabilizing planes depending from said wing planes and positioned substantially parallel to the axis of the curved plane, and smaller resistance planes carried by the wing planes, said resistance planes being inclined relative to said wing planes.
42. An aerocraft having a cross sectionally curved plane extending lengthwise of the craft, arched wing planes extending outwardly from said curved plane, a stability plane angular in cross section and positioned transversely to the curved plane, other stability planes depending from the wing planes, and propelling mechanism.
43. An aerocraft having a cross sectionally curved plane extending lengthwise of the craft, a stability plane angular in cross section and positioned transversely to said curved plane, propelling means, wing planes at the respective sides of the craft, each wing plane being provided at the forward end with a flexible tip, and means operable at will for changing the position of said flexible tip with reference to the surface of the wing plane.

the craft, wing planes at the respective sides of the curved plane, each wing plane being pointed toward the front end thereof and said wing plane being also pointed toward the rear end, propelling mechanism, a stability plane positioned transversely with respect to the curved plane, and other stability planes depending from the wing planes.

In testimony whereof I have signed my name to this specification in the presence of 10 two subscribing witnesses.
